DESIGN FOR A CUFF LINK OR THE LIKE

George Kingdon Lowe, Warwick, R. I., assignor to Campus Jewelry Products, Inc., Providence,
R. I., a corporation of Rhode Island

Application January 31, 1948, Serial No. 144,203

Term of patent 3½ years

(Cl. D17—7)

To all whom it may concern:

Be it known that I, George Kingdon Lowe, a citizen of the United States, residing in the city of Warkick, county of Kent, and State of Rhode Island, have invented a new, original, and ornamental Design for a Cuff Link or the like, of which the following is a specification, reference being had to the accompanying drawing, forming a part thereof.

Fig. 1 is a top plan view of a cuff link embodying my new design;

Fig. 2 is a front view of the cuff link; and
Fig. 3 is an end view of the same.

I claim:

The ornamental design for a cuff link or the like, substantially as shown.
GEORGE KINGDON LOWE.
